A. H. KUHLMANN

WEATHER STRIP

Filed March 10, 1922

INVENTOR
ARTHUR H. KUHLMANN,
by Roy M. Eilers ATTORNEY.

UNITED STATES PATENT OFFICE.

ARTHUR H. KUHLMANN, OF ST. LOUIS, MISSOURI.

WEATHER STRIP.

Application filed March 10, 1922. Series No. 542,684.

To all whom it may concern:

Be it known that I, ARTHUR H. KUHLMANN, residing at 6713 Washington Avenue, in the city of St. Louis and State of Missouri, have invented certain new and useful Improvements in Weather Strips, of which the following is a full, clear, and exact description, such as will enable others skilled in the art to make and use the same.

10 My invention relates to improvements in weather strips and more particularly to weather and water excluding devices as related to casement, or hinged, windows.

In the weather proofing of joints between the frames and sashes of casement windows, especially between the sills and lower rails, it is common to provide coacting elements in horizontal disposition for the exclusion of weather and to provide similarly disposed elements for the exclusion of water. By reason of such disposition of elements water from the exterior may, either by direct flow, or seepage, be conducted through the joint between the sill and rail.

25 It is my primary object to provide a weather proofing for windows, of the recited type, comprising elements disposed vertically, and to span the joint between the sill and sash whereby water flow or seepage

30 is conducted across such joint. A further object of my invention is to provide a weather proofing for casement windows, in which are combined coacting elements forming a horizontal seal for the exclusion of weather, or drafts, and elements forming a vertical water conductor spanning the recited, horizontal weather seal.

My improvements consist in the novel construction, arrangement and combination of parts as hereinafter fully, clearly and concisely described, definitely pointed out in my claims, and illustrated by the accompanying drawing in which—

Fig. 1 is a perspective view of a fragment 45 of the water table and deflector for securing to the lower rail of the window sash.

Fig. 2 is a perspective view of a fragment of the sill strip.

Fig. 3 is a perspective view of a fragment 50 of the sash strip.

Fig. 4 is a transverse sectional elevation showing a sill and sash equipped with the strips as shown in Figs. 1, 2 and 3.

55 Fig. 5 is a perspective view of a fragment of a water table and deflector for a rabbeted sash, and

Fig. 6 is a view similar to Fig. 4 showing the strip of Fig. 5 as mounted, and in use.

Referring by numerals to the drawing, 7 60 designates the sill, 8 the stop thereon, 9 the lower rail of the sash, and 10 the rabbet of the sash for fitment over the stop 8. In my drawing I show such parts in their common, usual arrangement wherein, by reason 65 of the requirement of relative lateral movement of the sash over the sill, the horizontal faces of the rabbet in the sash are spaced relative to the horizontal faces of the sill and stop.

70 The recited spacing of the sill and sash elements forms an open joint through which weather and water may pass from out to in.

75 For the exclusion of weather, or drafts, I provide a strip 11, which I secure to the horizontal face of the stop 8 by means such as the screws 12, and which has at its inner margin a tongue, 13, preferably residing in a plane above the body of the strip. Secured to the horizontal face of the rabbet, over 80 the stop, is a strip 14, which carries at its inner margin a hook 15 arranged to embrace or surround the tongue, 13, of the described sill strip 11, and to coact therewith to form a seal preventing movement of weather, 85 drafts, or air currents in either direction through the otherwise open joint between the sill and sash.

90 For the exclusion of water I provide a shield 16, which is supported by the sill and spans the outer mouth or side of the open joint between the sill and sash, as shown in Fig. 4. Obviously water from the exterior is conducted by the shield from above the joint to below the joint.

95 By preference, the shield is provided with a trough, such as 17, and by further preference, as shown best in Fig. 2 the shield and trough are formed as an integral extension 100 of the sill strip 11. At its upper end the shield is bent or inclined inwardly to approximate the sash and thus partially close its otherwise open top.

105 For the further and fuller closing of the open topped shield I provide a water table 18, in the form of a strip, which is secured to the sash, for movements therewith, having a deflector 19, for residence inside or behind the shield 16, and inclined or bent to parallel the shield and which functions to conduct such water as may enter over the top of the shield to the trough. For drain-

age of the trough I provide weep holes such as 20.

By preference the upper margin of the water table is bent inwardly to the end that when desired it may be imbedded in the sash.

By further preference the water table comprises a reentrant 21 forming a shed or cover overlying the upper margin of the shield 16.

By the construction and arrangement of the described elements it will be apparent that water from the exterior can neither flow nor seep through the joint between the 15 sill and sash.

In the form shown in Figs. 5 and 6 the construction and operation is identical with the described form except for the water table, 18^a. In this form the re-entrant 21^a 20 is shaped for fitment in a rabbet 22 formed in the outer face of the sash.

I claim:

1. A weather proofing for casement windows, comprising an element composed of a 25 shield, a trough and a tongue and arranged for securement to a sill, an element having a hook and arranged for securement to a sash and an element comprising a table, a deflector and a re-entrant portion and arranged 30 for securement to a sash, said tongue and hook adapted to form a weather seal in the

joint between the sill and sash and said table, deflector, reentrant, shield and trough adapted to form a water seal for said joint.

2. In a weather proofing for casement windows a strip for securement to the outer face of the window sash, having a deflector inclining downwardly and outwardly and a reentrant forming a shed above said deflector, a second strip for securement to the 40 horizontal face of a rabbet formed in the sash, having a hook at its inner margin, and a third strip having a portion for securement to the horizontal face of a sill-stop, a tongue on said portion for engagement in the recited hook, an outstanding trough-shaped portion and a shield above the trough-shaped portion inclined inwardly and upwardly to overlie the recited deflector and to underlie said shed.

3. A weather proofing for casement windows comprising a strip for securement to the outer face of a sash, a strip for securement to an underneath face of a sash, and a strip for securement to a sill, said last mentioned strip arranged to co-act with the first mentioned strip to exclude water from the joint between the sash and sill and to co-act with said second mentioned strip to exclude air from said joint.

ARTHUR H. KUHLMANN.
